Primary Examiner — Jennifer L Rempfer*Assistant Examiner* — Varun Salil Kamat(74) *Attorney, Agent, or Firm* — Mehdi (Afshin) Zamanpour(57) **CLAIM**

The ornamental design for a bookcase, as shown and described.

DESCRIPTION

FIG. 1 is a front perspective view of a bookcase, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The surface shading on the outer surfaces of the article, shown with series of triple concentric semi-circular dashes, indicates a plush effect.

The dashed broken lines depict portions of the bookcase that form no part of the claimed design.
